BOIL-OFF APPARATUS FOR TEXTILE FABRICS

Victor T. Fahringer, Clarksville, Va., assignor to
Robbins Mills, Inc., New York, N. Y., a corpora-
tion of New York

Application January 31, 1951, Serial No. 208,763.

8 Claims. (Cl. 68—157)

1

This invention relates to an apparatus for processing textile fabrics and more especially to an improved boil-off apparatus through which textile fabrics are passed before the dyeing and finishing operations so as to remove the sizing from the yarns in the textile fabric. In order that fabric may be completely immersed in and thoroughly penetrated by the boil-off liquid as it is passed through a boil-off apparatus, it has been found desirable to introduce a fabric into the boil-off bath and to progress the same through the boil-off bath for a predetermined length of time in the form of spaced loops whereby the entire surface of the fabric is disposed to the boil-off liquid. However, since all textile fabrics are relatively lighter than the liquid in which the sizing is boiled off, difficulty has been experienced in maintaining the loop configuration of the fabric as it passes through the boil-off liquid since the loops formed would tend to float on the boil-off liquid and would collapse as the fabric passed into the liquid thus resulting in opposed portions of the loops engaging each other and resulting in the fabric being unevenly penetrated by the boil-off liquid, which, of course, would result in the fabric being marked or spotted in the dyeing or finishing processes.

It is therefore, the primary object of this invention to provide an improvement in a boil-off apparatus including means for distending the preformed spaced loops in the fabric as it is made to progress through the boil-off bath to thus insure that the entire surface of the fabric is exposed to the boil-off liquid and which not only results in a greater efficiency and economy of operation but also permits a continuous boil-off process and whereby speed of operation is increased and insures that the fabric will be completely immersed in and penetrated by the boil-off operation.

It is another object of this invention to provide carrier means or conveyor means for the fabric having means associated therewith for forming loops from the fabric and subsequently passing the fabric in loop form through the boil-off liquid and means for causing the loops to maintain an inverted attitude as they progress through the boil-off liquid, this last-named means including means for circulating the boil-off liquid upwardly from the lowermost portion of the boil-off apparatus and through the loops disposed thereabove.

Some of the objects of the invention having been stated, other objects will appear as the description proceeds, when taken in connection with the accompanying drawings, in which—

2

Figure 1 is a left-hand side elevation of the improved boil-off apparatus with certain parts being omitted and other parts being broken away in order to fully illustrate the primary features of the invention;

Figure 2 is an elevation looking at the left-hand end of Figure 1 with the upper portion thereof broken away and showing the rear or discharge end of the apparatus;

10 Figure 3 is an enlarged fragmentary elevation showing the manner in which the conveyor chain is constructed;

Figure 4 is an elevation, with parts in section, looking substantially along the line 4—4 in Figure 2 but with the central portion of the tank being broken away so as to illustrate the driving means for the apparatus;

Figure 5 is a vertical sectional view taken substantially along the line 5—5 in Figure 1 and showing the various sprocket wheels but omitting all of the sprocket chains for purposes of clarity;

Figure 6 is an enlarged vertical sectional view taken substantially along the line 6—6 in Figure 5;

20 Figure 7 is a top plan view of the apparatus looking down at the top of Figure 1 and omitting all of the various movable parts of the apparatus so as to clearly illustrate the arrangement of the piping;

Figure 8 is a schematic isometric view being partially exploded and showing the arrangement of the piping for circulating the boil-off liquid through the apparatus and also showing the piping for maintaining a uniform temperature of the boil-off liquid, the tank and all movable parts of the apparatus being omitted for purposes of clarity;

Referring more specifically to the drawings, the numeral 10 broadly designates the boil-off 30 tank having a bottom 11, opposed side walls 12 and 13 and opposed end walls 14 and 15 which are suitably joined together so as to retain a suitable boil-off liquid indicated at 16. For purposes of description, it is to be assumed that the rear of the apparatus is disposed in the direction of movement of the material therethrough and, therefore, the end walls 14 and 15 shall be hereinafter referred to as the front and rear walls, respectively, and the side walls 12 and 13 shall be hereinafter referred to as the left-hand and the right-hand side walls, respectively.

It will be observed in Figures 2 and 5 that there is provided a pair of longitudinally extending vertically disposed partitions 20 and 21 which 45 are spaced inwardly from the respective side walls 12 and 13 and which extend from the bot-

tom 11 upwardly and terminate a substantial distance short of the upper edges of the end walls 14 and 15. These partitions 20 and 21 have secured to the outer or opposed surfaces thereof vertically disposed frame members or standards 22 to 25, inclusive, and 26 to 29, inclusive, respectively, which are secured thereto by any suitable means such as by bolts 30. These bolts 30 also serve to secure opposed ends of transverse frame members 34, 35, 36 and 37 to the proximate surfaces of the partitions 20 and 21. It will be observed in Figure 7 that opposed ends of the transverse frame member 34 are secured to the partitions 20 and 21 between the vertically disposed frame members 22 and 26, the transverse frame members 35 being disposed between the vertically disposed members 23 and 27, the transverse frame member 36 being secured between the vertically disposed frame members 24 and 28 and the transverse frame member 37 being secured between the vertically disposed frame members 25 and 29. In Figure 1, it will be observed that these transverse frame members are spaced slightly above the floor or bottom 11 and are merely provided to support a pair of pipes to be later described.

The front end of a horizontally disposed frame member 40 is suitably secured, as by bolts 41, to the upper end of the vertically disposed frame member 22 which extends substantially above the tank 10 and this horizontally disposed frame member 40 is secured at its rear end, as by bolts 42, intermediate the ends of the vertically disposed frame member 25. The vertically disposed frame members 23 and 24, which are spaced between the vertically disposed frame members 22 and 25, are also secured intermediate their ends to the horizontally disposed longitudinally extending frame member 40 by any suitable means such as bolts 43. A similar longitudinally extending frame member 44 disposed at the same elevation as the frame member 40, is suitably secured to the inner surfaces of the vertically disposed frame members 26, 27, 28 and 29, as by bolts 45 (Figure 7).

Referring to Figure 1, the fabric to be processed is generally designated at F and is directed from a suitable source at the front end of the apparatus to a roller 50 which is suitably journaled at opposed ends thereof in bearing blocks 51 suitably secured to the vertically disposed frame members 23 and 27, this roller extending transversely of the apparatus and being disposed between these frame members 23 and 27. The fabric F then partially encircles a suitable cloth feeding roll 52 covered by a suitable friction material such as cloth which is fixed on a shaft 53 suitably journaled at opposed ends thereof in bearing blocks 54 which are suitably secured to the vertically disposed frame members 23 and 27 above the bearing blocks 51.

The fabric F then extends downwardly from the roll 52 and passes between a pair of closely spaced cascade boxes 57 and 57' (Figures 1, 5 and 6) both of which are identical except being opposite hand and therefore only the cascade box 57 will be described in detail and the parts of the cascade box 57' will bear the same reference characters as those parts associated with the cascade box 57 with the prime notation added. The cascade boxes 57 and 57' rest upon spaced beams 58 and 58' respectively which are welded at opposed ends to side frame members 40 and 44. The cascade box 57 is closed at opposed ends thereof by end walls 60 and 61 and these

end walls 60 and 61 are joined by a top wall 62, a bottom wall 63 and an outer wall 64. It will be observed in Figure 6 that the cascade boxes 57 and 57' are provided with respective upwardly diverging walls 65 and 65' which extend from the proximate edges of the bottom walls 63 and 63' and terminate short of the proximate edges of the upper or top walls 62 and 62'. The respective end walls 60 and 60' are penetrated by pipes 66 and 66' which extends outwardly and are suitably connected for communication to a pipe 70 which is a part of the piping diagram to be later described.

The pipes 66 and 66' direct boil-off liquid to the cascade boxes 57 and 57' respectively, and thus the boil-off liquid overflows the proximate walls 65 and 65' of the cascade boxes 57 and 57' and tends to urge the fabric F downwardly between the boxes and also assists in forming loops 20 thereof in a manner to be later described.

The fabric F then extends downwardly past a roller 71 to a conveyor broadly designated at C. This roller 71 is journaled at opposed ends thereof for rotation in the free ends of a pair of pivoted arms 72 and 73 which extend upwardly and rearwardly at an angle and are pivotally connected, as at 74, to the remote surfaces of the longitudinally extending frame members 40 and 44.

Referring to Figure 3, there is shown a relatively small section of the conveyor C which comprises a pair of sprocket chains 75 and 76 which are spaced substantially apart from each other and in parallel relation to each other. The chains 75 and 76 are roller chains and alternate pins 77 thereof have enlarged opposed ends of transverse bars or poles 80 suitably secured thereto and the pins disposed between the alternate pins each have an inwardly extending stub shaft or relatively short bar 81 extending inwardly therefrom, the proximate ends of the bars 81 on the conveyor chain 75 being spaced substantially from the proximate ends of the corresponding end of the bars 81 on the conveyor chain 76. The length of the roller 71 between the reduced journal portions thereof is such that the roller will rest upon either the pins or stub shafts 81 at opposed ends thereof or upon the enlarged end portions of the transverse bars 80 as the conveyor C moves in a clockwise direction therebeneath in Figure 1.

It will be noted that the upper reaches of the chains 75 and 76 of the conveyor C are slidably supported on angle bars 75a and 76a, respectively, which are suitably secured, as by welding, to the vertically disposed frame members 23 and 24 and 27 and 28, respectively. The upper reach of the conveyor C moves in the opposite direction from that in which the fabric F is passed through the machine. This conveyor is driven, in a manner to be later described, at a speed proportionate to the speed at which the speed roll 52 is driven, in a manner which will also be later described, to thus cause the roll 52 to direct a predetermined length of fabric to the conveyor C so as to form loops 82 in the fabric as it is directed to the conveyor.

The roll 71 is provided to insure that the fabric will be properly laid over the upper surfaces of the transverse bars 80 of the conveyor as these bars 80 move through the upper reach of the conveyor C and the cascade boxes 57 and 57' cause the boil-off liquid to cascade downwardly and to thus tend to urge the fabric F downwardly between adjacent transverse bars 80 of the conveyor chain C so as to form the loops 82 of predetermined length.

The conveyor chain 75 (Figure 1), which is an

endless chain, is mounted on sprocket wheels or rollers 83 to 88, inclusive. All of the sprocket wheels 83 and 85 to 88, inclusive, are idler sprockets or rollers and are mounted on respective stub shafts 90 to 94 and the stub shafts 90, 91 and 94 are suitably secured to the inner surfaces of the respective vertically disposed frame members 24, 22 and 25. The stub shafts 92 and 93 are suitably secured to the inner faces of respective horizontally disposed frame members 95 and 96 which are welded at opposed ends thereof to the respective vertically disposed frame members 22 and 23 and 24 and 25, respectively (Figure 1).

The chain 76 has been omitted from Figure 4 for purposes of clarity but is mounted in a like manner on the sprocket wheels 100 to 105, inclusive, shown in Figure 4. The sprocket wheels 100, 102, 103, 104 and 105 are rotatably mounted on respective stub shafts 106 to 110, inclusive. The stub shaft 106 is fixedly mounted on the vertically disposed frame members 28, the stub shaft 107 is fixedly mounted on the vertically disposed frame member 26 and the stub shaft 108 is fixedly mounted on a horizontally disposed frame member 111 which is welded at opposed ends thereof to the proximate surfaces of the vertically disposed frame members 26 and 27. The stub shaft 109 is fixedly mounted in a horizontally disposed frame member 114 which is fixedly mounted at opposed ends thereof to the proximate surfaces of the vertically disposed frame members 28 and 29. The stub shaft 110 is fixedly mounted on the vertically disposed frame member 29.

The sprocket wheels 84 (Figure 1) and 101 (Figure 4) are fixedly mounted on stub shafts 115 and 116, respectively, which are rotatably mounted in suitable bearing blocks 117, only one of which is shown in Figure 1, and which are suitably secured to the outer surfaces of the vertically disposed frame members 23 and 27.

The loop formations 82 of the fabric F are maintained in a manner to be later described as the conveyor C moves in a clockwise direction in Figure 1 and as the lower reach of the conveyor C moves out of the boil-off liquid 16 in the left-hand end of Figure 1, the fabric is withdrawn therefrom over a suitable roll 120 which is preferably cloth covered and is fixedly mounted on a shaft 121 rotatably mounted at opposed ends thereof in suitable bearing blocks 122, only one of which is shown in Figure 1, suitably secured to the outer surfaces of the vertically disposed frame members 24 and 28. The fabric then extends from the upper surface of the roll 120 to a similar roll 125 which is also preferably cloth covered and then extends downwardly to be folded or otherwise disposed of in any desired manner.

The roll 125 is fixedly mounted on a shaft 126 rotatably mounted in bearing blocks 127 which are suitably secured to the upper surfaces of a pair of horizontally disposed frame members 130 and 131 which extend forwardly and are suitably secured, as by bolts 132 to the upper ends of vertically disposed frame members 25 and 29, respectively.

Referring to Figure 4, there is shown a suitable framework generally designated at 135 and which has a lower platform 136 and an upper platform 137. The lower platform 136 has an electric motor 140, a suitable variable speed unit 141 and a gear reduction unit 142 thereon. The electric motor 140 has wires 143 and 144 extending therefrom which are adapted to extend to a suitable source of electrical energy, not shown, for energizing the electric motor 140. The electric motor 140 has a shaft 145 extending therefrom on which a pulley 146 is mounted, this pulley 146 having a belt 147 thereon which extends to a pulley 150.

The pulley 150 is fixed on a shaft 151 projecting from the variable speed unit 141. Thus, the motor pulley 146 imparts rotation to the shaft 151 through the belt 147 and pulley 150 which will, in turn, transmit rotation to a shaft 153 which also extends from the variable speed unit 141. Since there are many types of variable speed units which may be employed and which are provided with an input shaft 151 and an output shaft 153, a detailed drawing and description of the variable speed unit is believed unnecessary. The output shaft 153 of the variable speed unit 141 has a sprocket wheel 155 and a pulley 156 fixedly mounted thereon.

The sprocket wheel 156 has a chain 157 mounted thereon which is also mounted on a sprocket wheel 160 fixedly mounted on an input shaft 161 of the gear reduction unit 142. Since there are many different types of gear reduction units which may be employed, a detailed description of the gear reduction unit 142 is deemed unnecessary, it being sufficient to state that the input shaft has suitable gearing associated therewith for transmitting rotation to an output shaft 162 projecting from the gear reduction unit 142. This output shaft 162 has a sprocket wheel 164 fixedly mounted thereon on which a sprocket 165 is mounted. This sprocket chain 165 extends upwardly and is also mounted on a sprocket wheel 166 fixedly mounted on a transverse shaft 167. The transverse shaft 167 is rotatably mounted in bearing blocks 170 slidably secured to the front surfaces of the vertically disposed frame members 22 and 26.

The shaft 167 is also rotatably mounted in a bearing block 171 (Figures 2 and 5) which is suitably secured to an angle bracket 172 which is, in turn, suitably secured as by bolts 173, to the side wall 13 of the boil-off tank 10. As is most clearly shown in Figure 5, the shaft 167 also has a pair of sprocket wheels 175 and 176 fixedly mounted thereon which are disposed adjacent the outer surfaces of the respective vertically disposed frame members 22 and 26. The sprocket wheels 175 and 176 have respective sprocket chains 177 and 178 mounted thereon (Figure 2) which extend upwardly and forwardly at an angle as shown in Figure 4 and are mounted on respective sprocket wheels 181 and 182 which are fixed on the outer ends of the respective shafts 115 and 116. The sprocket chains which connect the respective sprocket wheels 175 and 176 to the sprocket wheels 181 and 182 have been omitted from Figure 5 for purposes of clarity. It is thus seen that the output shaft 153 on the variable speed transmission 141 transmits movement to the conveyor C in a clockwise direction in Figures 1 and 4 through the connections heretofore described since the sprocket wheels 84 and 101 are fixed on the respective shafts 115 and 116 on which the respective sprocket wheels 181 and 182 are also mounted.

Assuming the boil-off tank 10 to be empty, the boil-off liquid is initially introduced to the tank from a suitable source through a pipe 187 (Figures 7 and 8) having a manually operable valve 188 interposed therein for controlling the flowing of the liquid from a suitable source, not shown, through the pipe 187 to a pair of axially aligned pipes 189 and 190 to which the pipe 187 is connected by means of a pipe T 191. The pipe 189 is connected to an elbow 192 which is con-

connected by means of a nipple 193 to an elbow 194. The elbow 193 has one end of a nipple 195 connected thereto, the other end of which is connected to a pipe T 196. The pipe T 196 has a suitable centrifugal pump 197 connected thereto which has a shaft 200 extending therefrom (Figures 2 and 7) which is, in turn, connected to a motor shaft 201 by means of a suitable coupling 202. The motor shaft 201 extends from an electric motor 203 (Figure 2) having wires 204 and 205 extending therefrom to a suitable source of electrical energy, not shown, for energizing the electric motor 203 to, in turn, drive the centrifugal pump 197.

This centrifugal pump is provided as a means of circulating the boil-off liquid introduced to the pipes 189 and 190 through the various pipes connected thereto as indicated by the arrows in Figures 7 and 8 for purposes to be later described. A pipe T 206 connects the pipe T 196 with an elbow 207 to which a pipe 210 is connected. The pipe 210 is connected to another pipe T 211 having one end of a nipple 212 connected to the other end thereof, a suitable manually operable control valve 213 being interposed in the pipe 212. The other end of the pipe 212, that is, the end of the pipe 212 remote from the pipe T 211 is connected to a perforated pipe 214 by means of an elbow 215, this perforated pipe resting upon the transverse frame members 36 and 37 and having a plurality of upwardly directed bores, nozzles or ports 216 in the upper wall thereof. It is evident that this pipe 214 penetrates the end wall 15 of the tank 10 which should be suitably sealed so as to prevent the contents of the tank 10 from leaking around the pipe 214.

Also connected to the pipe T 211 is a nipple 220 which is connected to a transverse pipe 221 by means of a pair of elbows 222 and 223 and a nipple 224. This pipe 221 is suitably closed at its free end and is provided with a plurality of spaced nozzles or jets 225 in each of which a suitably manually controlled valve 226 is interposed to control the flow of boil-off liquid through these nozzles 225 as it is circulated therethrough by virtue of the centrifugal pump 197.

These nozzles 225 penetrate the wall 15 of the tank 10 at substantially the same level as the sprocket wheels 88 and 105 to thus cause the liquid to surge inwardly at this point and to assist in maintaining the formation of the loops 82 as they move thereby and immediately before the loops are withdrawn from the transverse rods 80 on the conveyor chain C.

The pipe 190 is connected to a nipple 230 by means of a pipe elbow 231, this nipple 230 being connected at its other end to a pipe T 232 to one branch of which a pipe 233 is connected, this pipe 233 having a suitable manually operable control valve 234 interposed therein. The end of the pipe 233 remote from the pipe T 232 is connected to discharge pipe 235 by means of a pipe elbow 236. This discharge pipe 235 penetrates the front wall 14 of the boil-off tank 10 and rests upon the transverse frame members 34 and 35 and extends longitudinally to the center of the tank 10 and terminates in axial alignment with and adjacent to the inner end of the discharge pipe 214. The proximate ends of the discharge pipes 214 and 235 are closed, as at 237 and 238, respectively (Figure 1). The discharge pipe 235 is also provided with a plurality of bores, nozzles or ports 216 in the upper surface thereof identical to the bores 216 in the pipe 214 to thus direct the boil-off liquid 75

upwardly from the pipes 214 and 235 as the boil-off liquid is circulated therethrough by means of the centrifugal pump 197. This causes the boil-off liquid to surge upwardly to thus maintain the formation of the loops 82 as they move with the lower reach of the conveyor C as shown in Figure 1.

The branch of the pipe T 232 has a pipe 243 connected thereto which is connected to a transversely extending pipe 244 by means of elbows 245 and 246 and a nipple 247. This pipe 244 is disposed at a slightly higher elevation than the upper edge of the wall 14 of the tank 10 and has a plurality of inwardly and downwardly directed nozzles or jets 250 extending therefrom, each of which has a manually operable control valve 251 interposed therein for controlling the flow of the boil-off liquid therethrough. These nozzles are formed in the manner described so that the free ends thereof terminate immediately above the mean level of the boil-off liquid as it flows upwardly from the discharge pipes 214 and 235 over the edges of the partitions 20 and 21. Upon the desired amount of liquid being introduced to the tank 10, the valve 188 is closed and, if so desired, the usual ingredients may then be added to the boil-off liquid after the boil-off liquid 16 has been heated to a desired temperature, in a manner to be later described.

The liquid is caused to flow from the pipes 214 and 235 upwardly and outwardly over the partitions 20 and 21 and a pair of return pipes 254 and 255 are disposed between the partition 20 and the wall 12 and the partition 21 and the wall 13, respectively. The pipes 254 and 255 may rest upon the floor or bottom of the tank if so desired. The pipes 254 and 255 have elbows 256 and 257 on the free ends thereof which face upwardly and are open at their upper ends to thus direct the boil-off liquid into the pipes 254 and 255. The pipe 254 is connected to a pipe elbow 260 which is connected to one end of a pipe 261. This pipe 261 also has a pipe T 262 thereon, the branch of which is connected to the pipe 255. The end of the T 262 remote from the pipe 261 is suitably connected to one side of the centrifugal pump 197 and therefore the pump 197 will cause the liquid to return thereto through the pipes 254 and 255 and will circulate the liquid through the pipes connected thereto by means of the pipe T 196 to thus cause the liquid to discharge through the respective pipes 214 and 235.

In order to initially heat the liquid 16 after the desired amount has been introduced to the tank 10 and when the valve 188 has been closed, the electric motor 203 is stopped so as to stop operation of the centrifugal pump 197 and live steam is introduced to the tank through the discharge pipes 214 and 235 in a manner to be presently described.

Referring to Figure 2, it will be observed that the pipe T 206 has one end of a pipe 265 connected thereto in which a suitable manually operable control valve 266 is interposed which is opened after the desired amount of liquid 16 has been introduced to the tank 10 in a manner heretofore described. This pipe 265 has a pipe 270 connected thereto by means of an elbow 271 and this pipe 270 is connected to the branch of a pipe T 272 to which live steam is directed from a suitable source, not shown, through a pipe 273 connected to one end thereof. The pipe T 272 has a steam pipe 274 connected to the end thereof remote from the end to which the pipe 273 is connected and this pipe 274 is suitably connected to a

closed steam coil 276, which preferably rests upon the upper surface of the bottom 11 of the tank 10. The free end of the steam coil 276 has a suitable steam trap 277 on the free end thereof through which the usual condensation resulting from the steam in these pipes may be discharged in a well known manner.

Upon the boil-off liquid 16 being initially heated to the desired temperature, the manually operable valve 266, is closed and the electric motor 203 is again energized to cause the liquid to circulate upwardly from the bottom of the tank and over the partitions 20 and 21 and downwardly to return to the pump 197. The steam will be directed continuously to the steam coil 276 and, therefore, the temperature of the liquid 16 may be maintained during the circulation thereof. It is evident that suitable thermostatic controls may be provided, if so desired, for maintaining the uniform temperature in the liquid 16 during circulation thereof.

Now, as heretofore stated, the speed at which the fabric F is initially introduced to the conveyor C may vary relative to the speed of the conveyor C so as to vary the length of the loops 82 formed in the fabric F as the fabric is draped over the transverse rods 80 of the conveyor C.

Also due to possible shrinkage of the material and various other effects which may be produced as the loops 82 progress through the liquid 16, the speed at which the fabric F is withdrawn from the conveyor C may also be variable. Therefore, by referring to Figure 4, it will be observed that the upper platform 137 of the framework 135 has a pair of variable speed transmission units 280 and 281 mounted thereon which are provided with suitable input shafts 282 and 283, respectively, which are driven in a manner to be later described to, in turn, impart rotation to respective output shafts 284 and 285.

The input shaft 282 of the variable speed transmission 280 has a sprocket wheel 286 fixedly mounted on each end thereof adjacent opposed sides of the variable speed transmission 280, only one of which is shown, and one of these sprocket wheels 286 has a sprocket chain 287 mounted thereon and the other of the sprocket wheels 286 has a sprocket chain 290 mounted thereon. The sprocket chain 287 is also mounted on the sprocket wheel 155 associated with the first-named variable speed transmission unit 141 and therefore rotation is thus imparted to the shaft 282. The sprocket chain 290 transmits rotation from the other of the sprocket wheels 286 on the shaft 282 to the shaft 283 by means of a sprocket wheel 291 fixed on the shaft 283 projecting from the variable speed transmission 281. The shaft 283 of the variable speed transmission 281 transmits rotation, by conventional means, not shown, associated with the variable speed transmission 281, to the shaft 285 which has a sprocket wheel 293 fixedly mounted thereon. A sprocket chain 294 is mounted on the sprocket wheel 293 and is also mounted on a sprocket wheel 295 fixed on a shaft 296 which is rotatably mounted in suitable bearing blocks fixed to the upper surface of the upper platform 137. The shaft 296 also has a pinion 297 fixed thereon which meshes with a pinion 309 fixed on a shaft 301 which is rotatably mounted in suitable bearing blocks supported on the upper platform 137.

This shaft 301 also has a sprocket wheel 304 fixedly mounted thereon on which a sprocket chain 305 is mounted. This sprocket chain 305 extends upwardly and is mounted on a sprocket

wheel 306 which is fixedly mounted on the outer end of the horizontally disposed shaft 53 on which the feed roller 52 is fixedly mounted to thereby impart rotation to the roller 52.

The shaft 282 (Figure 4) imparts rotation to the shaft 284 through conventional mechanisms, not shown, disposed within the variable speed transmission 280 and this shaft 284 has a sprocket wheel 307 fixedly mounted thereon which transmits rotation to the roll 120 (Figure 1) through intervening connections which are identical to the connections between the sprocket wheel 293 and the roll 52 and therefore a detailed description of these connections will not be given and like parts associated with the sprocket wheels 307 bear the same reference characters as like parts associated with the sprocket wheel 293 with the prime notation added. The sprocket wheel 306 is, of course, fixedly mounted on the transverse shaft 121 heretofore described. This shaft 121 also has a sprocket wheel 312 (Figure 4) fixedly mounted thereon, on which a sprocket chain 313 (Figure 2) is mounted, this sprocket chain 313 also being mounted on a sprocket wheel 314 which is fixedly on the shaft 126 heretofore described, this shaft 126 having the roll 125 mounted thereon.

It is thus seen that the speed at which the two cloth covered rolls 52 and 120 are driven may be varied relative to each other as well as relative to the speed at which the conveyor C is driven and the discharge roller 125 is driven at the same speed at which the roller 120 is driven. The variable speed transmissions 141, 280 and 281 may be of any conventional type such as the type which is manufactured by Link-Belt Company, 2045 West Huntington Park Avenue, Philadelphia, Pennsylvania, and a complete description of which is provided in their book No. 1274 entitled "P. I. V. Gear Positive Variable Speed Transmission," fourth edition dated March 1935.

It is thus seen that I have provided an improved boil-off apparatus including a continuously moving conveyor having means thereon for receiving the folds of fabric directed thereto and for forming the loops 82 therein and whereby the loops are directed reversely of the direction in which the fabric is initially directed to the machine and downwardly into the boil-off liquid 16. As the loops enter the liquid, the liquid is forced along the upper surface of the fabric in the direction in which the loops are facing and immediately above the upper surface of the liquid in the tank 10 to thus cause the loops to lay substantially flat or horizontal as they are initially moved into the liquid bath. This insures that the loops will be properly distended as the fabric moves downwardly on the lower reach of the conveyor C. As the loops progress through the liquid bath along with the lower reach of the conveyor C, the liquid surges upwardly at a relatively high pressure thus causing the loops to remain distended in an inverted manner as is clearly shown in Figure 1 with the result that the fabric will be evenly immersed and penetrated by the boil-off liquid. As the loops 82 progress upwardly at an angle as shown in the left-hand portion of Figure 1, the jets of boil-off liquid from the nozzles 225 will tend to throw these loops inwardly above each other so that they are still projected into the boil-off liquid throughout their entire movement through the boil-off liquid. This also insures that the loops 82 will not become entangled in the bars or rods 80 or the projections of the conveyor C

as the fabric is withdrawn from the conveyor C by the rollers 120 and 125 disposed thereabove.

By moving the fabric to be treated through the boil-off liquid in a plurality of spaced inverted loops, maximum penetration as well as uniform penetration of the fabric is achieved resulting in a boil-off process which is more efficient and of a higher quality than has heretofore been possible.

In the drawings and specification, there has been set forth a preferred embodiment of the invention and although specific terms are employed, they are used in a generic and descriptive sense only and not for purposes of limitation, the scope of the invention being defined in the claims.

I claim:

1. An improved apparatus for boiling-off textile fabrics comprising a boil-off tank adapted to contain a boil-off liquid, a horizontally disposed endless traveling conveyor having its lower reach disposed in the boil-off tank and submerged in the boil-off liquid and having its upper reach disposed above the liquid level, means for forming the fabric to be treated into depending loops on the upper reach of said conveyor at a point in advance of the point where the loops enter the boil-off liquid in said tank and means disposed below the lower reach of the conveyor for directing jets of the boil-off liquid upwardly through the lower reach of the conveyor for inverting the loops upwardly as they are progressed through said liquid so as to insure uniform penetration of the fabric by the boil-off liquid.

2. An improved apparatus for boiling-off textile fabrics comprising a boil-off tank adapted to contain a boil-off liquid, a horizontally disposed endless traveling conveyor having its lower reach disposed in the boil-off tank and submerged in the boil-off solution and having its upper reach disposed above the liquid level, means for forming the fabric to be treated into depending loops at spaced points on the upper reach of said conveyor in advance of the spaced points entering the boil-off liquid in said tank and means for inverting the loops upwardly as they are progressed through said liquid so as to insure uniform penetration of the fabric by the boil-off liquid, said inverting means comprising means for withdrawing the liquid from the tank and reintroducing the same into the tank in the form of a plurality of upwardly directed jets disposed at points beneath said loops to hold said loops in upwardly inverted position.

3. An improved apparatus for boiling-off textile fabrics comprising a boil-off tank adapted to contain a boil-off liquid, a horizontally disposed endless traveling conveyor having its lower reach disposed in the boil-off tank and having its upper reach disposed above the liquid level, means for forming the fabric to be treated into depending loops on the upper reach of said conveyor to cause the loops to be passed through the boil-off liquid in said tank, means for inverting the loops upwardly as they are progressed through said liquid so as to insure uniform penetration of the fabric by the boil-off liquid, said means for inverting the loops comprising at least one pipe disposed beneath the path of travel of the lower reach of the conveyor, said pipe having a plurality of upwardly directed bores therein and means for circulating the boil-off liquid through said pipes and bores under pressure to cause the fluid to surge

upwardly from said bores and to thus invert the loops.

4. An improved apparatus for boiling-off textile fabrics comprising a boil-off tank adapted to contain a boil-off liquid, means for introducing a fabric into said tank in a plurality of spaced preformed depending loops, means for passing the fabric in loop form through the boil-off liquid and means disposed below the loops as they pass through the liquid for directing jets of the boil-off liquid upwardly against said loops for causing the loops to maintain an inverted attitude as they progress through the boil-off liquid, said last-named means including a perforated pipe disposed below the loops and a pump for withdrawing liquid from the boil-off tank and forcing the same through the perforated pipe under pressure upwardly from the lowermost portion of the boil-off tank and through the loops disposed thereabove.

5. An improved apparatus for boiling-off textile fabrics comprising a boil-off tank adapted to contain a boil-off liquid, an endless conveyor having upper and lower horizontally disposed reaches, the lower reach being submerged in the boil-off liquid and the upper reach being disposed above the liquid level, means for introducing a fabric to the upper reach of said conveyor and forming it into a plurality of depending loops, means driving said conveyor for passing the fabric in loop form through the boil-off liquid in said tank and means for causing the loops to maintain an inverted attitude as they progress through the boil-off liquid comprising means for circulating the boil-off liquid under pressure and releasing the same in jets directed upwardly from the lowermost portion of the boil-off tank and through the loops disposed thereabove.

6. An apparatus for boiling-off textile fabrics comprising a boil-off tank adapted to contain a boil-off liquid, an endless pole conveyor having upper and lower reaches, roller means disposed above the tank for supporting the upper reach above the liquid level and other roller means disposed in the boil-off liquid and near each end of the tank for supporting the lower reach of the conveyor, means for introducing said fabric to the upper reach of said conveyor, means positioned adjacent the point of introduction of said fabric to said conveyor for positioning said fabric in spaced depending loops about the poles on said conveyor, said boil-off tank having end walls and bottom walls, each of said end walls having adjacent the inside surface thereof a plurality of transversely spaced nozzles, a plurality of nozzles disposed in the bottom of said boil-off tank, a pump for withdrawing boil-off liquid and forcing the same through the nozzles at the ends of the tank and through the nozzles in the bottom of the tank to distend the loops of fabric as they enter the boil-off liquid to maintain the loops of fabric in an inverted distended position as they are passed through the liquid in said boil-off tank and to maintain the loops in distended condition as they leave the boil-off tank and means for removing said fabric from said endless pole conveyor after said fabric has been passed through said boil-off tank.

7. An improved apparatus for boiling-off textile fabrics comprising a boil-off tank adapted to contain a boil-off liquid, said tank having a frame extending thereabove, a plurality of rollers mounted in the frame above the liquid level and also within the tank near each end thereof and below the liquid level, an endless pole conveyor

supported by said rollers thus forming upper and lower reaches, a cloth feeding roll supported in said frame, means for driving said conveyor and means for driving said cloth feeding roll in timed relation to said conveyor so that fabric extending from said cloth feeding roll to said conveyor will be positioned about the poles on said conveyor in a plurality of spaced depending loops, means on said frame for assisting in positioning said fabric about said poles on said conveyor, 10 said boil-off tank being provided with a plurality of nozzles at the ends and bottom thereof, a piping system connected to all of said nozzles and connecting with the boil-off tank, a pump in said piping system for withdrawing boil-off liquid from the tank and forcing the same through all of said nozzles to thus distend and invert the loops of fabric on said conveyor and hold the same in spaced relation to each other as the conveyor moves said loops through the boil-off liquid, means for heating and maintaining said boil-off liquid at a constant temperature and said frame also having at least one second cloth roll 15 thereon for removing the fabric from said conveyor after it has passed through the boil-off liquid.

8. An improved apparatus for boiling-off textile fabrics comprising a boil-off tank adapted to contain a boil-off liquid, said tank having a frame extending thereabove, a horizontally disposed endless pole conveyor having an upper reach supported by said frame above the liquid level, rollers disposed near each end of the tank and below the liquid level for supporting the lower reach of said conveyor in the lower portion of said boil-off tank and below the liquid level, a cloth feeding roll supported by said frame above the upper reach of the conveyor, means for driving said conveyor and means for driving said cloth feeding roll in timed relation to said conveyor so that fabric extending from said cloth feeding roll to said conveyor will be

positioned about the poles of the upper reach of said conveyor in a plurality of spaced depending loops, means on said frame for assisting in positioning said fabric about said poles on said conveyor, said boil-off tank being provided with a plurality of nozzles at the ends and along the bottom thereof, all of which are directed towards the conveyor, a piping system connected to all of said nozzles and having an intake end communicating with the lower portion of said tank, a pump in said piping system for withdrawing boil-off liquid from the tank and forcing it through all of said nozzles under pressure to thus distend and invert the loops of fabric on 10 said conveyor and to hold the same in spaced relation to each other as the conveyor moves said loops through the boil-off liquid, means for heating and maintaining said boil-off liquid at a constant temperature, said frame also having at least one second cloth roll thereon for removing the fabric from said conveyor after it has passed through the boil-off liquid, said means for positioning the fabric on the pole conveyor including a pair of closely spaced transversely extending cascade boxes having their proximate walls of lesser height than their other walls, means for introducing boil-off liquid to said cascade boxes and said fabric extending between said cascade boxes whereby boil-off liquid therein will cascade 15 from the proximate walls against said fabric to drive the same downwardly between the poles on said conveyor.

VICTOR T. FAHRINGER.
